UNITED STATES PATENT OFFICE.

HEINRICH HÖRLEIN, OF VOHWINKEL, NEAR ELBERFELD, GERMANY, ASSIGNOR TO
FARBENFABRIKEN VORM. FRIEDR. BAYER & CO., OF ELBERFELD, GERMANY, A
CORPORATION OF GERMANY.

PHENYLETHYLMALONIC ESTER.

1,036,624.

Specification of Letters Patent. Patented Aug. 27, 1912.

No Drawing.

Application filed January 31, 1912. Serial No. 674,473.

To all whom it may concern:

Be it known that I, HEINRICH HÖRLEIN, doctor of philosophy, chemist, citizen of the German Empire, residing at Vohwinkel, 5 near Elberfeld, Germany, have invented new and useful Improvements in Phenylethylmalonic Esters, of which the following is a specification.

I have found that the hitherto unknown 10 phenylethyl-malonic esters can be obtained by treating the phenylmalonic esters with ethylbromid. The new esters are valuable intermediate products for the production of substituted barbituric acids which are valuable 15 therapeutic compounds. Upon treatment with caustic alkali they are split up into alcohols and phenylethylmalonic acid melting at 160° C.

The esters of the present invention have 20 the following general formula:

(R=alkyl, aralkyl, aryl).

25 In order to illustrate the new process more fully the following example is given, the parts being by weight:—236 parts of phenylmalonic ester

30 and 120 parts of ethyl-bromid (BrC_2H_5) are

added to a solution of 23 parts of sodium in 230 parts of alcohol (free from water). The resulting mixture is then heated to boiling in a vessel provided with a reflux condenser until the liquid shows a neutral 35 reaction to lacmus. The liquid is filtered, the alcohol is distilled off and the ester is isolated in the usual way. It is a limpid oil boiling at 166° C. under a pressure of 12 mm. 40

I claim:—

1. As new products, the phenylethylmalonic esters being liquids which are split up by the action of caustic alkali into alcohols and the phenylethylmalonic acid, substantially as described. 45

2. The phenylethylmalonic ethyl ester, being a limpid oil, boiling at 166° C. under a pressure of 12 mm., and being split up by the action of caustic alkali into alcohol and the phenylethylmalonic acid, substantially as described. 50

In testimony whereof I have hereunto set my hand in the presence of two subscribing witnesses.

HEINRICH HÖRLEIN. [L.S.]

Witnesses:

HELEN NUFER,
A. NUFER.
